No. 792,412.

PATENTED JUNE 13, 1905.

A. A. GRAY.

OILER.

APPLICATION FILED SEPT. 23, 1904.

UNITED STATES PATENT OFFICE.

ALBERT A. GRAY, OF IOLA, KANSAS.

OILER.

SPECIFICATION forming part of Letters Patent No. 792,412, dated June 13, 1905.

Application filed September 23, 1904. Serial No. 225,631.

To all whom it may concern:

Be it known that I, ALBERT A. GRAY, a citizen of the United States, residing at Iola, in the county of Allen and State of Kansas, have invented new and useful Improvements 5 in Oilers, of which the following is a specification.

My invention relates to oilers, and especially to that class of oilers known as "over-head" oilers.

The object of my invention is to provide an oiler supplied with a force-pump and mounted upon a pole of any desired length and so arranged that the pump may be operated from any point along the pole to deliver through a discharge-tube a positive flow of oil.

A further object of my invention is to provide an oiler especially adapted for oiling 20 line-shafting situated above or below the operative.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within 30 the scope of the claims without departing from the spirit or sacrificing any of the advantages of the invention.

In the drawings, Figure 1 is a view in side elevation of my improved oiler. Fig. 2 is a vertical sectional view of my oiler, showing in outline the various forms of discharge-tubes to be used in connection therewith. Fig. 3 is a detail sectional view of the cap adapted to close the supply-opening and showing the 40 air-inlet valve disposed within said cap. Fig. 4 is a detail sectional view of the check-valve located at the lower end of the discharge-tube. Fig. 5 is a detail sectional view of the stuffing-box and gland through which the 45 piston-rod enters the pump-cylinder.

Like characters of reference designate corresponding parts throughout the several views.

In its preferred form my improved oiler is 50 mounted upon a pole A by means of a ferrule

B. The ferrule B is provided with a slot C, through which is passed an offset portion of the piston-rod D. The piston-rod D is passed through stuffing-box E, provided with packing F, upon which gland G is adapted to exert pressure. A pump-cylinder H is disposed axially within a hollow receptacle I and is provided near its lower end with openings K, forming communication between the cylinder H and the receptacle I. The stuffing box E is secured within the lower end of pump-cylinder H and a gasket J disposed between said stuffing-box E and the surface of receptacle I. Within the upper end of pump-cylinder H is secured a cap L, provided with an opening longitudinally therethrough and with a valve-seat formed in the lower end of said longitudinal opening. A valve is disposed within said longitudinal opening adapted to coöperate with the valve-seat and provided with a follower M, adapted to vary the pressure of the spring upon the valve. Within the upper and outer end of the cap L is secured a discharge-tube N, which may be straight or curved in any desired degree of curvature. A gasket O is disposed between the cap L and the exterior surface of receptacle I to produce a tight joint. A coupling P is secured to the lower end of piston-rod D, extending from without 80 the slot C. Guide-rings Q are secured to the pole A, and through said guide-rings Q a rod R is slidably placed and secured to the coupling P, thus forming a continuation of the piston-rod D along and parallel with the pole 85 A. Upon the end of the said piston-rod D, disposed within the pump-cylinder H, is secured a washer S, and upon said washer is placed a valve T, preferably of leather and held in contact with the washer S by means 90 of lock-nut V. A cap U, provided with a shoulder W, is adapted to close the supply-opening in plate X, secured to receptacle I. The cap U is provided with an opening extending longitudinally therethrough, and 95 within said opening is disposed a valve-seat member Y, with a valve therein operated by spring Z.

The operation of my improved oiler is as follows: With the various parts assembled as 100

shown in Fig. 2 the cap U may be removed and the receptacle I filled with oil. The cap U may then be replaced, preventing the spilling of oil from the receptacle. The oil with-
5 in the receptacle I will pass through open-
ings K into pump - cylinder H. A down-
ward displacement of the rod R will draw the
piston-rod D and the valve T downward
10 within the cylinder H, the oil passing freely
about the valve T during such descent. An
upward movement of the rod R and valve T
will force the oil through cap L and dis-
charge-pipe N through the check-valve, and
15 air will be admitted through the valve at Y
to occupy the place of the oil drawn into the
cylinder H by the upward movement of the
valve, thus delivering oil in positive quan-
tities to any position which may be reached
20 by the tube N.
25 It is obvious that minor changes may be
made in the form and construction of my im-
proved oiler without departing from the
spirit of my invention or the scope of the
claims.
25 Having thus described my invention, what
I claim as novel, and desire to secure by Let-
ters Patent, is—
30 1. An oiler comprising a hollow receptacle,
a pump-tube disposed within the receptacle,
a discharge-tube communicating therewith,
a check-valve mounted adjacent to the dis-
charge-tube and within the pump-tube, a
35 piston mounted to reciprocate within the
pump-tube and all mounted upon a pole and
provided with means for reciprocating the
piston from any point along the pole.
2. An oiler comprising a hollow receptacle,
40 a removable cap adapted to close an opening
provided for the introduction of a fluid
within the receptacle, a valve adapted to ad-
mit air into the receptacle as the fluid is re-
moved therefrom, a pump-cylinder disposed
45 within the receptacle, a discharge-tube com-
municating with the pump-cylinder, a check-
valve disposed between the pump-cylinder
and discharge-tube, a piston mounted to re-
ciprocate within the cylinder, a piston-rod
passing into the pump-cylinder through a

stuffing-box and secured to the piston, and all
mounted upon a pole and provided with 50
means for reciprocating the piston from a
point near the lower end of the pole.

3. An oiler comprising a hollow receptacle,
a removable cap adapted to close an opening
provided for the introduction of a fluid with-
in the receptacle, said cap being provided
with an opening longitudinally therethrough,
a tubular member removably secured within
the opening through the cap, a valve-seat pro-
vided within the outer end of the tubular 60
member, a spring-operated valve adapted to
cooperate with the valve-seat and so mount-
ed within the tubular member as to permit
the passage of air therethrough as the fluid is
removed, a pump-cylinder disposed within 65
the receptacle and provided with openings at
one end to admit fluid thereto from the re-
ceptacle, a cap removably secured within the
one end of the cylinder and provided with
an opening extending longitudinally there-
70 through, a valve-seat formed within one end
of the opening, a spring-controlled valve dis-
posed for cooperation with the valve-seat, a
discharge-tube removably secured one end
within the opening, a valved piston mounted 75
to reciprocate within the cylinder, a stuffing-
box removably secured within the end of the
cylinder opposite the discharge-tube, a pis-
ton-rod passing through the stuffing-box and
80 secured to the piston, a ferrule removably se-
cured to the stuffing-box and provided with
a longitudinally-disposed slot, a curve pro-
vided in the piston-rod adapted to pass out-
wardly through the slot, a pole removably 85
secured within the ferrule and a rod disposed
parallel with the pole and connected with the
piston-rod and affording means for the recip-
rocation of the pump from any point along
the pole.

In testimony whereof I affix my signature 90
in presence of two subscribing witnesses.

ALBERT A. GRAY.
